HAND CONTROLLED HYDRAULIC DRIVE
MECHANISMMerton H. Arms, Springfield, Vt., assignor to
Bryant Chucking Grinder Company, Springfield, Vt., a corporation of Vermont

Application August 22, 1938, Serial No. 226,135

9 Claims. (Cl. 60—52)

This invention relates to mechanism for manually controlling the speed of motion of a hydraulic drive mechanism, and more particularly to a movable carriage such as may be employed, for example, to support either the tool or the work for a machining operation.

One object of this invention is to provide such a manual control which can be applied readily to hydraulically actuated machines, and in accordance with which the speed of travel of the part moved may be controlled by the operator at will, or the speed controlled automatically by the setting of the normal machine controls.

For a more complete understanding of this invention, reference may be had to the accompanying drawings, in which

Figure 1 is a perspective view of an internal grinding machine embodying the invention.

Figure 2 is a plan view of a traversing stop cam.

Figure 3 is a diagrammatic view of a portion of the hydraulic system and showing the manual speed control incorporated therein.

Figure 3a is a fragmentary view similar to a portion of Figure 3, but showing the selector valve in its dressing axial position.

Figures 3k to 3n, inclusive, are detail sectional views on lines k—k to n—n, respectively.

Figure 4 is a view similar to Figure 3 but showing a modification.

Figure 5 is a view similar to a portion of Figure 4, but showing one of the hydraulic valves in a different axial position as when the traversing carriage has passed beyond one of its normal grinding limits and is in the wheel truing portion of its path of travel.

For purpose of illustration this invention is shown as embodied in a hydraulically actuated internal grinding machine of the type shown in my Patent 2,176,985 granted October 24, 1939, for Grinding machine, though it should be understood that it is not limited to any particular type of machine, or in its broadest aspects to any particular type of hydraulic control mechanism. Reference may be made to this patent for details of the hydraulic system not fully shown herein.

The machine shown for purpose of illustration comprises a bed 1, as shown in Figure 1, having spaced upwardly extending portions 2 and 3 supporting aligned hydraulic cylinders 4 and 5. The pistons of these cylinders are connected to a supporting bar 6 on which is mounted a grinding head 7. This head 7 may carry thereon a grinding wheel motor 8 connected by suitable driving

means (not shown) to a wheel shaft 9 supporting a grinding wheel 10 on its outer end. At 11 is shown a casing for a work support in which work is carried for rotation as is well understood in this art. The supporting bar 6 with its carriage 7 is traversed to bring the grinding wheel 10 into or out of the work and to effect traverse of the work when in contact therewith, by hydraulic power applied to one or the other of the hydraulic cylinders 4 and 5, a fluid such as oil being used in the well understood manner. The hydraulic cylinders constitute a reversible hydraulic motor for moving the carriage, being provided with passages 21 and 22, alternatively pressure and discharge passages, depending on the direction of motion of the motor.

A hydraulic system for accomplishing this is shown diagrammatically in Figure 3, there being shown at 35 an oil pump by which oil is taken from the supply tank 36 and delivered through a pipe 37 to a main valve casing 39 containing the various control valves which will later be described. A relief valve set to maintain a predetermined constant supply pressure is shown at 38 for discharging excess oil from the supply line 37 into the tank. The oil is returned from the main valve casing through the discharge line 31 and a back pressure valve 40 which insures sufficient pressure in the system at all times, say, about ten pounds, to prevent the entry of air. The oil at a pressure, say, of 100 to 120 pounds is conducted through the supply line 37 through the main casing. Three main control valves are employed, a pilot valve 41, a reversing valve 42, and a selector valve 43. A control handle 30 is fixed directly to the pilot valve 41. This pilot valve has an axial movement substantially parallel to the wheel traverse direction and a rocking movement. The reversing valve 42 has an axial movement only. The selector valve 43 has both axial and rocking motions. The angular motions of the selector valve are produced through angular motions of the pilot valve through a gear 45 on the pilot valve meshing with a partial gear 46 shown in dotted lines at 47, which, in turn, meshes with a gear 48 on the selector valve with which it also has sliding engagement.

To the pilot valve 41 is secured a cam 100 shown in detail in Figure 2, this having indicated different angular positions corresponding to similar angular positions of the handle 30 and indicated as "grind," "dress," "stop" and "fast." When the handle 30 is in "grind" position, as shown in Figures 3 and 4, the carriage traverses automatically in one and then the other direction for the

normal grinding cycle. The reciprocation of the bar 6 causes rotation in one or the other direction of a rock shaft 84 journaled crosswise of the power cylinder and carrying a cam drum 83. The driving connection between the bar 6 and the rock shaft 84 may be of any suitable description, such, for example, as a rack 87 supported to move with the bar 6 engaging a pinion 86 on the shaft 84 as shown in Figure 3. The cam drum 83 supports three cam dogs 80, 81, and 135. The cam dogs 80 and 81 co-act with the cam plate 100 so that when the handle 30 is in grinding position, they strike on opposite sides of this cam and move the pilot valve 41 axially adjacent to the ends of the stroke of the grinding wheel to make reverse connections to start the traverse in the reverse direction.

Figure 3 shows the pilot and selector valves in their grinding positions. When the handle 30 is turned to "dress" position, by turning it clockwise as viewed from the left in Figure 3, valves 41 to 43 will be turned to their "dress" positions. In the "dress" position the cam dog 80 will clear the cam plate 100 so that the carriage may have an extended traverse outwardly from the work to an extent sufficient to permit the cam dog 135 to contact the upper end of a lever 137, rocking this lever and moving the selector valve 43 to the right into the position of Figure 3a where it opens suitable ports leading to a suitable wheel dressing mechanism, the details of which are not pertinent to the present invention. The speed of traverse throughout the grinding portion of this stroke and the extended or truing portion may be placed under the control of the hand-operated speed control. The parts shown in Figure 3 are in the position to effect grind traverse to the left from the normal right hand grind limit of traverse.

The oil under pressure passes from the pump 35 through the passage 37 around the selector valve 43, as shown by the arrows, to the reversing valve 42 around the reversing valve passage 420 and through the passage 22 to the end of the right hand cylinder. In this position of the parts, also, the fluid under pressure in the passage 37 passes through passage 370, around the reversing valve through the annular passage 37a which is always open, up to the pilot valve through passage 371, through valve passage 410, and through the passage 60 to the right hand end of the reversing valve 42, which is thus held in its left hand position. The pipe 21 leading to the left hand cylinder 4 at the same time is discharging, as shown by the arrows, into the passage 66. In the machine shown in my Patent No. 2,176,985, this discharge takes place through other mechanism not material to this invention and hence not shown herein.

From the passage 66, the discharge takes place past the reversing valve in either of two paths, one of which leads through the reversing valve passage 421, through the passage 67 to the pilot valve 41, and around its neck 411, to the upper face of a throttle valve 70 and also to the intake of the metering device P. The other path is from the reversing valve passage 421 through the pipe 68 and past the needle valve 69 into the said discharge passage 67. Flow from the passage 67 is past the valve 70 into the passage 71 through the ports 71a and 71b (the valve 43 being positioned 45° counterclockwise from its Figure 3m position), into and through channels 430 and 431 to the return passage 31. In the shifting

of the pilot valve from its left hand position shown in this figure, the discharge passage 67 is at first closed, the neck 411 of this valve moving out of line with this passage 67, so that all the discharge has to take place past the needle valve at 69, thus acting to slow the traverse of the carriage 7 before the actuation of the reversing valve 42 to start the stroke to the right.

A passage 61 leading from the left hand end of the reversing valve 42 to the pilot valve 41 discharges to the pipe and passage 62 when fluid under pressure is directed to the right hand end of the valve 42. These passages 60 and 61 are reversed in function, the passage 61 becoming the pressure passage and the passage 60 the discharge passage, when the pilot valve 41 is moved axially to the right from the position shown in Figure 3. This is because the pilot valve passage 413 then connects the upper end of the pressure passage 371 to the passage 61, cutting out the connection to the pipe 62, while the pilot valve passage 410 cuts out communication to the pressure passage 371 and connects the passage 60 to the discharge pipe 62. The pressure then passing to the left hand end of the reversing valve 42, and being discharged from the right hand end of this valve, causes this valve to move to its right hand position, shutting off pipe 68, connecting the pressure passage 370 through the valve passage 421 to the pipe 66, and connecting the pipe 22 with the discharge passage 73 through the reversing valve passage 420, thus reversing the direction of traverse. A throttle valve 74 in the passage 73 then performs the same function as the throttle valve 69 to control the speed of traverse, as previously described.

Discharge reaches the valve 70, and this valve being open more or less, passes this valve into the passages 71 and 150 and from the passage 150 it may reach a passage 130 past a throttle valve 131. Discharge from 130, 71 and 150 is controlled by the selector valve 43 to the discharge pipe 31 leading back to the tank 36 and in dress angular position of Figures 3a, 3k to 3n the passage 130 only is always open to the passage 31 through the ports 130a and 130b and through valve passages 432 and 433. With the valve 43 in its left hand position as in Figure 3 return flow is through the passage 71 as before described, and when the valve 43 is turned 90° counterclockwise from its Figure 3n position, the passage 150 will be connected through the ports 150a and 150b and channels 430 and 431 and the return passage 31 and 130 will be connected by the ports 130a and 130b to the channels 430 and 431. The valves 70, 131, the selector valve, and the supply tank and the pump 35 may be by-passed to the pressure pipe 37 through the metering device P, which transfers fluid under pressure from the discharge passage 67 directly to the pressure passage 37.

In the normal automatic actuation of the machine, the valve 70 is partly open so that the discharge of fluid past it governs the normal speed of traverse of the wheel slide, the metering pump P then being idle. This valve 70 is provided with an actuating shaft 700 (see Figure 1) which extends out through the front face of the machine and is provided with an actuating handle 701. By turning this handle the valve 70 may be shut off entirely, whereupon the only discharge from the left hand cylinder is through the metering device P. This metering device is provided with a hand actuated crank 702 so that by turning this at the rate desired, the rate of discharge

of the fluid from the left hand cylinder is controlled, thus controlling the speed of traverse of the carriage. While the metering device may be of any suitable type, it is indicated somewhat diagrammatically as being a gear pump. Such a pump, being of the constant delivery type in which the rate of flow remains in at least substantially constant ratio to the speed of actuation of the pump permits the operator to "feel" the action of the grinding wheel or other tool so that he can gage the speed of traverse and the speed of rotation of the handle in accordance with such feel.

At 103 is positioned a check valve which prevents any possibility of the passage of fluid in the opposite direction from the pressure line 37. It will be noted that the connection to this pressure line causes the oil to be drawn from the left hand hydraulic cylinder by actuation of the metering device P and forced into the right hand hydraulic cylinder, thus to positively control the axial position of the wheel slide and to cause it to traverse at a rate determined by the rate of rotation of the handle 702. With the cam 100 as shown in Figure 2, in its dress angular position, it will not be contacted by the cam elements 80, 135 and 81 of the cam drum 83, and the limits of traverse may then be controlled by hand actuation of the handle 30 in moving the valve 41 axially. When the traverse has been carried as far as desired to the left, axial motion of the pilot valve 41 to the right will serve to reverse the direction of motion imparted by the metering device P, or by the automatic traverse control mechanism should the throttle valve 70 be open.

The throttle valve 131 controls the speed of traverse during the wheel truing operation.

When the selector valve 43 is in the angular dressing position both passages 71 and 150 are shut off as may be seen by an inspection of Figures 3m and 3n, and in both axial positions of this selector valve passage 130 is connected to the discharge passage 31 through the two similar valve passages 432 and 433.

In the showing of Figure 3, the metering device is placed in the discharge side of the fluid pressure circuit and acts to take fluid discharged from one of the hydraulic cylinders and to force this fluid into the other fluid pressure cylinder. It is, however, quite possible to place the metering device in the pressure side of the hydraulic system. Such an arrangement is illustrated diagrammatically in Figures 4 and 5. The metering device P' draws its fluid supply from the intake side of the pump 35 past a check valve 200, and delivers through a passage 201 to the passage 370 in the valve casing between the selector valve and the reversing valve. This passage 370, when the parts are in position to drive the carriage to the left, is connected through the reversing valve 42 into the line 22 leading to the right hand hydraulic cylinder. When the throttle valve 70 is open, the metering device P' is by-passed, fluid under pressure from the pipe 37 leading from the pump 35 passing through the passage 720 to the top of the throttle valve 70, past this valve, and through the passage 130, valve passages 432 and 433, to the passage 370, when the valve 43 is positioned as in Figure 5, or through passages 71 and 430 and 431 when the valve 43 is positioned as in Figure 4. Discharge from the other cylinder takes place through the pipe 66 past the reversing valve, line 67, past the pilot valve, and out through the discharge line 62 to the line 31, which returns to the tank 36. There is also a

second discharge through the passage 68 from the reversing valve 42 extending to the needle valve 69 and the line 61 which also leads into the discharge pipe 31. When the pilot valve 41 is moved to make the reverse connections, it first closes off the free passage 67 so that all the discharge must pass through the valve 69, thus limiting the discharge and thus slowing down the rate of traverse of the carriage before reverse connections are made to drive it in the opposite direction.

When the drive is in the opposite direction, the pilot valve 41 will be moved to the right from the position shown in Figure 4, whereupon the passage 22 to the right hand cylinder will be opened to discharge after the reversing valve 42 has been moved to its opposite extreme position, and the line 66 leading to the left hand cylinder will be supplied with liquid under pressure from the pressure line 37 and from the metering device P'. It will be noted here, however, that the pressure line for both directions of motion of the carriage passes from the pressure line 37 to the upper face of the throttle valve 70 through the passage 720, this valve 70 and also the dressing throttle valve 131 being then in the pressure side of the hydraulic system rather than in the discharge side as shown in Figure 3.

While there are other ports and passages shown than those which have been described, since they do not function as any portion of the present invention, they have not been further described, their functions having been pointed out in connection with my Patent No. 2,176,985 to which reference has already been made.

From the foregoing description of certain embodiments of this invention, it should be evident to those skilled in the art that various further changes and modifications might be made without departing from the spirit or scope of this invention as defined by the appended claims.

I claim:

1. In a machine having a traversing carriage, a reversible hydraulic motor mechanism for driving said carriage, a hydraulic system of which said motor forms a part, a supply pump in said system directing fluid under pressure to said mechanism, means in said system for selecting the direction of motion of said motor mechanism, means in said system for adjusting the rate of motion of said motor mechanism as driven by fluid pressure from said supply pump, and a manually actuated pump in said system introducing fluid under pressure between said supply pump and direction selecting means and bypassing said rate adjusting means, whereby when said rate adjusting means is set to prevent motion of said motor mechanism by fluid pressure derived from said supply pump, said motor mechanism may be actuated by said manually actuated pump at a rate proportional to the rate of actuation of said manually operated pump and in direction depending on the setting of said direction setting means.

2. In a machine having a traversing carriage, reversing hydraulic motor mechanism for moving said carriage, a pump supplying fluid under pressure to said mechanism, means for selecting the direction of motion of said mechanism, a flow rate regulating means between said supply pump and selecting means, and a manually operated pump connected to introduce fluid under pressure into the system between said regulating means and selecting means.

3. In a machine having a traversing carriage, a reversible hydraulic motor mechanism for moving said carriage, a pump supplying fluid under pressure to said motor mechanism, a discharge passage from said motor mechanism, means for selecting the direction of motion of said motor mechanism, and a manually operated pump connected to take fluid from said discharge passage and introduce it into the hydraulic system between said supply pump and said direction selecting means.

4. In a machine having a traversing carriage, a reversible hydraulic motor mechanism for moving said carriage, a pump supplying fluid under pressure to said motor mechanism, a discharge passage from said motor mechanism, an adjustable discharge rate means interposed in said discharge passage, means for selecting the direction of motion of said motor mechanism, and a manually operated pump connected to take fluid from said discharge passage between said motor mechanism and said discharge rate means and introduce it into the hydraulic system between said supply pump and said direction selecting means.

5. In a machine having a traversing carriage, hydraulic motor mechanism for moving said carriage, means supplying fluid under pressure to said motor mechanism, means controlling the direction of motion of said carriage, means normally controlling the speed of motion of said carriage by said motor mechanism, a manually operated metering fluid device connected to drive said motor mechanism, and manually controlled means actuatable to set said speed control means to prevent normal motion of said carriage, thereby to cause motion of said carriage to be produced solely by actuation of said device.

6. In combination with a machine having a movable carriage, a reversible hydraulic motor for moving said carriage in opposite directions and having a pair of ports acting alternatively as pressure and discharge ports, depending on the direction of motion of said motor, a fluid source, a pump for delivering fluid under pressure from said source, fluid pressure and discharge passages for said motor, a fluid directing means receiving fluid under pressure from said pump and connected to said ports and passages to determine the direction of motion of said motor, and means in the hydraulic system for regulating the flow of fluid under pressure from said fluid pressure passage to said motor and from said motor to said discharge passage and adjustable to prevent flow of fluid therethrough, of an operator-actuated constant delivery metering pump in said system in by-pass relation to said regulating means and operative when said regulating means prevents flow therethrough to produce flow of fluid from and to said fluid-directing means to produce motion of said motor at a rate determined by the rate of actuation of said device and in direction determined by the setting of said fluid-directing means.

7. In combination with a machine having a movable carriage, a reversible hydraulic motor for moving said carriage and having fluid passages for alternative supply and discharge depending on the direction of motion of said motor, a source of hydraulic pressure, a discharge passage, means for directing fluid under pressure from said source to one or the other of said motor passages while permitting flow to said discharge passage from the other or one fluid passage, and means in said discharge passage for regulating the rate of discharge and adjustable to stop said discharge, of an operator-actuable constant delivery metering device connected into said discharge passage in advance of said regulating means and discharging into the hydraulic system between said source and said directing means, whereby operation of said metering device when said regulating means stops said discharge removes fluid under pressure from said discharge passage on the motor side of said regulating means and forces it to said pressure supply to said directing means to cause motion of said carriage at a rate determined by the rate of operation of said metering device and in direction determined by the setting of said directing means.

8. In combination with a machine having a movable carriage, a reversible hydraulic motor for moving said carriage having fluid passages for alternative supply and discharge depending on the direction of motion of said motor, a fluid supply, means for forcing fluid under pressure from said supply, means for directing fluid from said forcing means to one or the other of said motor passages while permitting discharge of fluid from the other or one motor passage, means for regulating the supply of fluid from said forcing means to said directing means adjustable to stop said supply while permitting discharge, and an operator-actuated constant delivery metering device interposed between said supply and said directing means and by-passing said regulating means, whereby when said regulating means is adjusted to stop said supply operation of said metering device will supply fluid under pressure to said directing means to cause motion of said carriage at a rate determined by the rate of operation of said device and in direction determined by the setting of said directing means.

9. In a machine having a movable carriage, a fluid motor for moving said carriage, a fluid pressure operated valve for controlling the direction of such motion, a valve for controlling said reversing valve, means normally controlling the speed of motion of said carriage, a constant delivery metering device in the fluid circuit of said motor, and means for rendering inoperative said normal speed controlling means, whereupon the speed of motion of said carriage is controlled by operator actuation of said metering device and the direction of motion by the setting of said direction-controlling valve.

MERTON H. ARMS.
